(57) **CLAIM**

The ornamental design for a post-tension concrete splicing device, as shown and described.

DESCRIPTION

FIG. 1 is a perspective view of a post-tension concrete splicing device;

FIG. 2 is a front elevational view thereof, and a rear elevational view is a mirror image of the front elevational view;

FIG. 3 a top elevational view thereof;

FIG. 4 is a bottom elevational view thereof;

FIG. 5 is a right side view thereof;

FIG. 6 is a left side view thereof;

FIG. 7 is a section view along 7-7 in FIG. 5; and,

FIG. 8 is a section view along 8-8 in FIG. 2.

The broken lines defining threads illustrate environmental
subject matter only and form no part of the claimed design.
Surface shading lines form no part of the claimed design.

1 Claim, 4 Drawing Sheets
